UNITED STATES PATENT OFFICE

ELLIS J. G. PHILLIPS, OF AURORA, ILLINOIS, ASSIGNOR TO RICHARDS-WILCOX MANUFACTURING COMPANY, OF AURORA, ILLINOIS, A CORPORATION OF ILLINOIS

MOUNTING FOR FOLDING DOORS

Application filed March 9, 1929. Serial No. 345,652.

This invention relates to folding doors of the type comprising a plurality of leaves hinged together with the innermost leaf or leaves mounted to swing about pivots located adjacent to its inner margin, so that when folded the several leaves are side by side and substantially at right angles to the position they assume when unfolded or closed. Folding doors of this type may be made up of two or more leaves at one side only of a door opening, or where the door opening is quite wide, it is common to make the door as a whole in two units each made up of a plurality of leaves hinged together, the two units being mounted at opposite sides of the door opening so that when the leaves are unfolded they meet at the center of the opening or at some other intermediate point.

In folding doors of this character it is customary to support the outer leaf or leaves,—that is to say, all the leaves except those at the ends of the door opening,—on the floor or other support that forms the bottom of the door opening, and to provide top guides for the leaves in the form of hangers or rollers arranged to travel longitudinally of the opening as the door is folded or unfolded, and my invention has particularly to do with doors mounted in that way, and particularly with those in which the top support serves merely as a guide, and does not carry any part of the weight of the leaf with which it is connected.

The object of my invention is to provide an improved mounting for folding door leaves of the character above indicated, by which each leaf may readily be adjusted vertically to relieve against sagging, or to compensate for unevenness in the floor or other surface over which the door swings, which would tend to cause scraping of the leaf on such surface and interfere with its free swinging movement. I accomplish this object as illustrated in the drawings and hereinafter described. What I regard as new is set forth in the claims.

In the accompanying drawings,

Fig. 1 is a plan view showing a door composed of two units each having two leaves, which are shown in full lines in their closed

position, and in dotted lines in their folded position. The uprights marking the ends of the door opening are shown in section.

Fig. 2 is an end elevation, partly broken away, of one of the leaves, the tracks at the top and bottom of the door opening being shown in section; and

Fig. 3 is a partial side elevation of one of the leaves, partly broken away, with some parts in section.

Referring to the drawings,—4, 5 indicate upright members that mark the ends of a doorway, which, in the present instance, is shown as being equipped with a folding door made up of two similar units each comprising an inner leaf 6 and an outer leaf 7, the inner margin of the outer leaf being hinged to the outer margin of the inner leaf by hinges 8, which may be ordinary butt hinges.

The inner leaves 6 are pivotally mounted adjacent to their inner margins on top and bottom pivots 9 located adjacent to the uprights 4, 5, so that said leaves may swing freely either into position to close the door opening or into a position at approximately right angles to the doorway, as indicated by dotted lines in Fig. 1, and the outer leaves 7 swing either into a position of alinement with the leaves 6, as shown in full lines in Fig. 1, or fold up alongside the leaves 6 to completely open the doorway, as shown in dotted lines in said figure.

Extending longitudinally over the door opening is an inverted U-shaped track 10 having the marginal portions 11 of its side members 12 curved inwardly, or toward each other, as best shown in Fig. 2, the side members 12 being substantially vertical. The function of this track is to guide the upper portions of the outer leaves 7 as they are swung into or out of closed position, and to this end said leaves are provided, preferably adjacent to their outer margins, with horizontal rollers 13 mounted on vertical spindles 14 suitably secured to the upper marginal portions of said leaves. Preferably a bushing 15 is mounted on each spindle 14 between the roller 13 and the upper margin of the leaf, and the marginal portions 11 of the track are spaced apart far enough to permit the bush-

ings 15 to move freely between them, as shown in Fig. 2. The rollers 13 are slightly less in diameter than the space between the vertical members 12 of the track, and are adapted to bear on the inner surfaces of such vertical members, so that the track guides the upper portion of the leaf as it moves along it in opening or closing the door.

It will be observed that the guiding devices for the top of the leaf do not sustain its weight, but merely restrict its lateral movement, and to support such weight and provide for vertical adjustment of the leaf to keep it in proper relation to the floor or other support so that it will not scrape thereon, I provide each leaf 7 with a bottom support in the form of a pair of rollers 16 spaced apart and mounted on a horizontal pin or axle 17 that is carried by an upright stem 18. The lower portion of this stem extends between the two rollers 16, as shown in Fig. 2, and its upper portion is screw threaded, as shown at 19 in Fig. 3, and passes through an opening in a horizontal arm 20 that projects laterally from a vertical plate 21, as shown in said figure. This plate is the intermediate member of a housing that comprises also two flat plates 22, the outer marginal portions of which overlap and are secured to the end plate 21 by screws 23, thus forming a U-shaped housing that is adapted to be fitted upon one of the lower corners of the door leaf after the same has been cut away to provide a pocket 24 to receive the arm 20 and stem 19, together with a portion of the rollers 16, as best shown in Fig. 3. The plate 21 is inset in this pocket far enough so that its outer surface lies flush with the vertical marginal surface of the leaf, and it is screwed to the leaf by screws 25. The side plates 22 overlap the sides of the pocket, and they are secured to the leaf by screws 26, so that they enclose the pocket 24 and the parts located therein.

As has been said, the stem 19 extends through an opening in the arm 20, and it is swiveled therein so that it may rotate freely, but it may nevertheless be vertically adjusted with respect to the arm 20 to vary the extent to which the rollers 16 project below the lower margin of the leaf, or in other words, to vertically adjust the leaf with respect to the floor or other support. For this purpose the stem 19 is provided with a bushing 27 that has a bearing in the opening in the arm 20 and is somewhat longer than the thickness of said arm, to provide clearance. Said bushing may be threaded on the stem 19 or may be loosely mounted thereon, but in either case it is clamped to said stem by means of upper and lower nuts 28, 29 screwed on the stem respectively above and below the arm 20 and bushing 27. Preferably washers 30, 31 are interposed between the nuts 28, 29 and the adjacent ends of the bushing 27, as shown in Fig. 3. By this construction, by adjust-

ing either or both of the nuts 28, 29 to reduce the space between them, the bushing 27 may be tightly clamped to the stem 19 so that it will rotate therewith, and as the bushing has an elongated bearing in the arm 20 it holds the stem 19 upright and causes it to turn smoothly and without lateral oscillation. By adjusting the nuts 28, 29 the stem may be moved vertically through the arm 20 to adjust the position of the rollers 16 with respect to the bottom of the leaf.

As shown in Figs. 2 and 3, the rollers 16 are adapted to run on a horizontal track 31 sunk in the floor and provided with a longitudinal groove 32 into which the lower end 33 of the stem 19 extends. This lower extremity of the stem is preferably elongated, so that it cooperates with the groove 32 to hold the stem 19 against rotation with respect to the track 31 and consequently holds the rollers 16 in proper alignment with said track.

Owing to the swivel mounting of the stem, however, the door leaf may swing freely about a vertical axis represented by the stem 19 and the spindle 14 at the top of the door, which are in alignment with each other.

It will be understood that in folding doors having their leaves mounted to turn about vertical axes located midway between the vertical margins of the leaves, the position of the supporting devices above described would be correspondingly changed, instead of locating them at the outer corners of the leaves as shown and described.

I claim:

1. In a folding door comprising a leaf mounted to turn about a vertical axis with respect to a door opening and to move longitudinally of such opening, the combination with a door leaf, and a guide for the upper portion thereof, of a swivel mounting for the lower portion of the leaf, comprising a member adapted to be secured to the leaf and having a supporting portion, a screw threaded stem extending through an opening in said supporting portion, a bushing on said stem having a rotatable bearing in said opening, washers engaging the upper and lower ends of said bushing and extending over said supporting portion at opposite ends of said opening, said bushing being slightly longer than said opening to permit rotative movement of said washers relative to said supporting portion, nuts screwing over said threaded stem and engaging said washers, and a roller carried by said stem adapted to travel on a suitable horizontal surface below the leaf.

2. In a folding door comprising a leaf mounted to turn about a vertical axis with respect to a door opening, and to move longitudinally of such opening, the combination with the door leaf, a guide for the upper portion thereof comprising an inverted U-

- shaped track having vertical side portions, provided with inturned lower margins, and a roller carried by the door at its upper margin and adapted to bear on the vertical side portions of said track, of a swivel mounting for the lower portion of the leaf, comprising a member adapted to be secured to the leaf and having a horizontal arm, a screw-threaded stem extending through an opening in said arm, a bushing on said stem having a bearing in said opening, washers engaging the opposite ends of said bushing and extending over said arm above and below said opening, said bushing being slightly longer than said opening to permit said washer to rotate relatively to said arm, nuts screwing on said stem and adapted to engage said washers, and a roller carried by said stem and adapted to project beyond the lower margin of the leaf. 5 70

3. In a folding door comprising a leaf mounted to turn about a vertical axis with respect to a door opening and to move longitudinally of such opening, the combination with the door leaf, and a guide for the upper portion thereof, of a swivel mounting for the lower portion of the leaf, comprising a member adapted to be secured to the leaf and having a supporting portion, a screw threaded stem extending through an opening in said supporting portion and rotatably mounted therein, nuts screwing over said stem and below said opening for permitting said stem to be adjusted vertically relatively to said supporting portion, and a roller carried by said stem adapted to travel on a suitable horizontal surface below the leaf. 4. In a folding door comprising a leaf mounted to turn about a vertical axis with respect to a door opening and to move longitudinally of such opening, the combination with the door leaf, and a guide for the upper portion thereof, of a swivel mounting for the lower portion of the leaf, comprising a member adapted to be secured to the leaf and having a supporting portion, a stem extending through an opening in said supporting portion and rotatable therein, a bushing on said stem engaging within said opening, screw threaded means permitting vertical adjustments of said stem relatively to said supporting portion, and a roller carried by said stem adapted to travel on a suitable horizontal surface below the leaf. 5. A swivel mounting for folding doors comprising a series of door leaves, a member secured to the lower end of one leaf and having an arm extending horizontally thereto from in the longitudinal plane of the door leaf, plates secured on opposite sides of said leaves and secured to said first named member for rigidly maintaining the latter against lateral thrusts, a threaded stem extending through a vertical opening in said arm, an elongated cylindrical bushing adjustably secured on said stem for turning with the stem in said arm, said bushing being longer than the opening in said arm so that it extends slightly therefrom, threaded members disposed on said stem against the top and bottom surfaces of said bushing for compelling the bushing to rotate with said stem, and a roller carried by said stem and adapted to project beyond the lower margin of the leaf. 6. A swivel mounting for folding doors comprising a series of door leaves, a member secured to the lower transverse edge of one leaf and having an arm extending horizontally therefrom in the longitudinal plane of the door leaf, side plates secured on opposite sides of said leaf and secured to said first named member for rigidly maintaining the latter against lateral thrusts, a threaded stem mounted in said arm for supporting the door leaves, an elongated cylindrical bushing mounted on said stem and held between upper and lower threaded members to compel said bushing to turn with said threaded stem in said arm, said door leaf being rotatably supported on said lower threaded member, and a roller carried by said stem and adapted to project beyond the lower margin of the leaf. 80 85 90 95 100 105 110 115 120 125 130
